CASE AND OTHER CONTAINER FOR
CIGARETTES

Richard Fitz Power, London, England

Application January 14, 1936, Serial No. 59,047
In Great Britain January 22, 1935

16 Claims. (Cl. 206—41)

This invention relates to cases and other containers for cigarettes and has for its object to provide an improved form of case, simple and cheap to manufacture, not likely to get out of order, and which can be operated to produce a single cigarette from a row so that the cigarette can be easily removed from the case.

A cigarette case according to the present invention having means for removing a cigarette from the end of a row of cigarettes and advancing the cigarette through an apertured wall of the case and holding that cigarette in advanced position so that it can easily be removed from the case, wherein the cigarette is supported in the advanced position on a shoulder or detent engaging the end of the cigarette normally supported on the bottom of the case. Means may also be provided for lightly holding the cigarette in the advanced position by gripping the sides of the cigarette by oppositely disposed edges of openings in a tray or lid.

In one form of construction according to the present invention a cigarette case comprises in a wall to the side of the cigarettes a shoulder or resilient detent spaced from a wall in the case supporting the ends of the cigarettes, and an apertured wall opposite to said supporting wall, and slidable means formed to engage the end of a cigarette juxtaposed to the shoulder or detent to remove it from the supporting wall on to the shoulder or detent whereby the other end of the projected cigarette is correspondingly disposed in advance of its original position and is thereby segregated for easy removal.

Preferably the case comprises a lid slidable lengthwise of the cigarettes and having a depending finger to engage and displace a cigarette axially.

The depending finger may be a rigid abutment member or a resilient finger to engage the end of a cigarette or the finger may be in the form of a pin carried on a resilient member to be projected into the cigarette at the expense of straining the resilient member, which pin releases itself from the cigarette when pressure is removed from the resilient member.

The invention will now be described by way of example with reference to the accompanying drawings, wherein

Figure 1 shows one form of construction of tray;

Figure 2 shows a view of the left-hand end of Fig. 1;

Figure 3 shows a view looking at the right-hand end of Fig. 1;

Figure 4 shows a plan view of a lid for the tray in Fig. 1;

Figure 5 shows a view of Figure 4 looking from the left;

Figure 6 shows a modified form of tray;

Figure 7 shows a left-hand view of Fig. 6;

Figure 8 shows a section on the line VIII—VIII of Fig. 6;

Figures 9 and 10 show modifications.

In the various figures the like references designate the same or similar parts.

Referring first to Figs. 1 to 5, which show a construction suitable for forming the cigarette case by moulding processes e. g., in that material sold on the market under the registered trade-mark "Bakelite", the cigarette case comprises a tray 1 including a peripheral wall 2, 3, 4, 5 a shoulder 6 projecting from the wall 5 at the side of the cigarettes 7, and an aperture 8 in the wall 4, and a sliding lid 9 (Fig. 4) adapted to fit over the tray 1, having a finger 10 disposed to engage a cigarette juxtaposed to the shoulder 6 to project this cigarette through the aperture 8. The lid 9 is provided with flanges 11 for engaging with the walls 3, 5 of the tray 1 and with a flange 12 for overlapping the wall 4 so as normally to close the aperture 8, against cigarettes falling out.

The aperture 8 is preferably removed from the side wall 5 so that a cigarette is projected in a manner to permit free finger and thumb engagement, that is to say, there is no objection to the movement of disposing the finger and thumb, one to each side of the cigarette with a view to gripping the latter and removing it from the case.

If desired the lid flange 12 may be provided with an aperture 13 in offset relation to the aperture 8 so that a cigarette 16 which has been projected is lodged between one boundary wall 14 of the aperture 8 and the opposite boundary wall 15 of the aperture 13, which boundary walls engage the cigarette on opposite sides in planes parallel to the wall 4.

It will, however, be understood that the aperture 13 may be so dimensioned and disposed that the lid 9 may be returned to its normal position after projecting a cigarette so that the cigarette projects through the lid flange 12 after the lid has been closed.

In order to lead a cigarette to the aperture 8 as the lid 9 is slid to project a cigarette a tongue 17 is bent inwardly to provide a lead which directs the cigarette to the aperture. In use the box may be tilted to cause the cigarette 16 to

lie against tongue 17 and then the lid slid over the box so that tongue 18 projects the cigarette through aperture 8 until the inner end has passed by 6 which being behind will then hold 5 the cigarette projected whether or not the lid is returned.

In the modified form of construction shown in Figs. 6 to 8, particularly suitable for boxes formed from sheet metal or other sheet material, 10 the wall 5 of the tray 1 is slit transversely at 18 and longitudinally at 12, conveniently where the wall meets the bottom of the tray, to form a resilient tongue or abutment 20 disposed in advance of the wall 2.

15 The wall 4 is provided with an aperture 8 slightly removed from the side wall 5, this aperture being formed by slitting the wall 4 transversely and longitudinally where it meets the bottom of the tray 1, to form a tongue 17 which 20 is bent inwardly to provide a lead which directs a cigarette 16 to the aperture 8.

The side walls 3, 5 are provided with ribs 21 with which engage grooves such as 22 (Fig. 5) provided in the flanges 11 of the lid 9, so as to 25 guide the lid 9 as it is slid across the tray 1. Alternatively, the side walls 3, 5 may be provided with grooves and the flanges 11 with ribs.

The finger 10 at the rear of the lid 9 enters the tray 1 through an aperture 23 in the wall 30 2 of the tray so that a cigarette may be rolled on to the finger 10 and the relative movement between the lid 9 and the tray 1 projects a cigarette 16 through the aperture 8 in the tray 1 and disposes the cigarette on the lid for easy 35 removal, being tilted away from the side wall 11 of the lid 9. Instead of feeding a cigarette to the finger by gravity one or more springs such as 24 may be provided in the known manner which bear against a plate 25, or a bowed blade 40 spring may be disposed on the wall 3 and connected to the plate 25 as will be easily understood in the art.

In the projected position the end of the cigarette 16 within the tray 1, whichever construction is employed, is caught by the detent 20 or shoulder 6 and thus prevented from returning by axial displacement.

The apertures 8, 13 are so arranged that the lid may be returned to its closed position in effect being threaded over the cigarette 16 after the latter has been projected from the tray so that the case is closed and the cigarette is resting on the shoulder 6 or detent 20.

The projecting cigarette may then be removed easily by hand or with the mouth.

When the cigarette has been removed the flange 12 of the lid 9 prevents another cigarette coming out of the case unless and until it has been disposed on the shoulder 6 or detent 20 as 60 above described.

As shown in Fig. 9 the finger is in the form of a pin 27 carried by a resilient member 28 secured to the lid 9. This pin is adapted to be projected into the cigarette at the expense of 65 straining the resilient member 28. When the pressure is removed from the resilient member 28 the pin releases itself from the cigarette.

Whilst the invention has been described above in connection with cases in which cigarettes are 70 arranged in a row it will be understood that the invention may also be applied to cases in which cigarettes are retained in a bundle or in a plurality of rows. An arrangement as applied to cigarettes in a bundle is shown in Fig. 10. In 75 this case the tray 29 is of semi-circular cross

section and is provided on one side with a recess 30 to accommodate a cigarette 16. This cigarette is moved on to a shoulder 6 by relative movement of a lid as described in the preceding examples. The lid is mounted on the tray 29 in 5 the same manner as described above.

When the cigarettes are arranged in a plurality of rows the construction is on the same lines as shown in Fig. 10, a recess or housing such as 30 in Fig. 10 being provided in the case for 10 one cigarette at a time.

Cases according to the present invention may be formed of moulded material, for example, that material known under the registered trademark "Bakelite" or other plastic composition, 15 celluloid or the like or may be made in sheet material. The tray and the lid are preferably drawn from the sheet material.

The cases may also be made from cardboard and may be used as a carton or container in 20 which cigarettes are sold as well as a permanent cigarette case.

The present invention comprises not only the cigarette case as described but the means of projecting the cigarette from a case incorporated in 25 an ornament, articles of furniture or other commodities, for example, a lady's handbag or the like.

What I claim is:—

1. A cigarette case including means for engaging a cigarette at the end of a row of cigarettes in said case and partly projecting said cigarette from said case, through an apertured wall thereof and means for supporting said cigarette in its partly projected position, wherein the means for holding the cigarette in the partly projected position comprise a projection located inside said case, said projection engaging with the inner end of said cigarette. 30

2. In a cigarette case, means for removing a cigarette from the end of a row of cigarettes in said case, said means advancing said cigarette and for holding the same in a position projecting from said case so as to enable said cigarette to be removed easily including gripping elements associated with said case, said gripping elements lightly gripping the sides of the said cigarette in its projecting position and a projection located in said casing, said projection engaging with the inner end of the cigarette in the projected position. 40

3. In a cigarette case, means for removing a cigarette from the end of a row of cigarettes in said case, said means advancing said cigarettes and for holding the same in a position projecting from said case so as to enable said cigarette to be removed easily including a projection located inside said case, said projection engaging the inner end of the cigarette in the projected position. 50

4. A cigarette case comprising a base, two end walls and two side walls connected to said base, one of said end walls having an aperture therein towards one end thereof, a projection located intermediate the ends of the side wall adjacent said aperture, and slidable means adjacent said last mentioned side, said slidible means being adapted to engage the end of a cigarette juxtaposed to said projection so as to project said cigarette partly from said aperture and to engage its inner end in said projection. 60

5. A cigarette case comprising a base, two end walls and two side walls connected to said base, one of said end walls having an aperture therein towards one end thereof, a projection located intermediate the ends of the side wall adjacent said aperture, a lid mounted for sliding movement on 70

5 said case lengthwise of cigarettes contained in said case, and a depending element on said lid, said depending element being adapted to engage with a cigarette juxtaposed to said projection so as to project said cigarette partly from said aperture by moving it axially and engaging the inner end thereof with said projection.

6. A cigarette case according to claim 5 wherein said depending element is in the form of a rigid 10 abutment member.

7. A cigarette case according to claim 5 wherein said depending element is in the form of a depending resilient finger.

8. A cigarette case according to claim 5 wherein 15 said depending element is in the form of a resilient member, and a pin depending therefrom.

9. A cigarette case according to claim 5 including a flange on said lid, said flange overlapping said aperture when said lid is in the normally 20 closed position so as to close said aperture.

10. In a cigarette case, means for removing a cigarette from the end of a row of cigarettes in said case, said means advancing said cigarette and for holding the same in a position projecting from 25 said case through an apertured wall thereof so as to enable said cigarette to be removed easily, wherein said aperture is removed from the adjacent side wall so that the cigarette is projected in such a manner as to enable said cigarette to be 30 readily engaged.

11. A cigarette case according to claim 5 including a flange on said lid, said flange having an aperture therein, said last mentioned aperture being offset relatively to the aperture in the end wall.

35 12. A cigarette case according to claim 5 including a flange on said lid, said flange having an aperture therein, said last mentioned aperture being offset relatively to the aperture in the end wall, said apertures being so arranged relatively to one 40 another as to enable the lid to be returned to the normal position after projecting a cigarette.

13. A cigarette case comprising a base, two end walls and two side walls connected to said base, one of said end walls having an aperture therein 45 towards one end thereof, a projection located intermediate the ends of the side wall adjacent said aperture, a lid mounted for sliding movement on said case lengthwise of cigarettes contained in said case, and a depending element on said lid, said depending element being adapted to engage with a cigarette juxtaposed to said projection so as to project said cigarette partly from said aper-

ture by moving it axially and engaging the inner end thereof with said projection, and means for leading a cigarette to said aperture as it is being moved into its projected position.

14. A cigarette case comprising a base, two end 5 walls and two side walls connected to said base, one of said end walls having an aperture therein towards one end thereof, a projection located intermediate the ends of the side wall adjacent said aperture, a lid mounted for sliding movement on said case lengthwise of cigarettes contained in said case, and a depending element on said lid, said depending element being adapted to engage with a cigarette juxtaposed to said projection so as to project said cigarette partly from 15 said aperture by moving it axially and engaging the inner end thereof with said projection, and spring means for moving a cigarette into position for projection.

15. A cigarette case comprising a base, two 20 end walls and two side walls connected to said base, one of said end walls having an aperture therein towards one end thereof, a projection located intermediate the ends of the side wall adjacent said aperture, a lid mounted for sliding 25 movement on said case lengthwise of cigarettes contained in said case, and a depending element on said lid, said depending element being adapted to engage with a cigarette juxtaposed to said projection so as to project said cigarette 30 partly from said aperture by moving it axially and engaging the inner end thereof with said projection, and side flanges on said lid, said side flanges engaging said side walls.

16. A cigarette case comprising a base, two end 35 walls and two side walls connected to said base, one of said end walls having an aperture therein towards one end thereof, a projection located intermediate the ends of the side wall adjacent said aperture, a lid mounted for sliding movement 40 on said case lengthwise of cigarettes contained in said case, and a depending element on said lid, said depending element being adapted to engage with a cigarette juxtaposed to said projection so as to project said cigarette partly 45 from said aperture by moving it axially and engaging the inner end thereof with said projection, and side flanges on said lid, said side flanges engaging said side walls and co-operating ribs and grooves on said side walls and side flanges. 50

RICHARD FITZ POWER.
